EX

Nicholas Muller's Design for a pair of Statuettes

4188

PATENTED JUN 28 1870

Johann Peter Beckerberg
Charles Frederick
Nicholas Muller

Nicholas Muller

United States Patent Office.

NICHOLAS MÜLLER, OF NEW YORK, N. Y.

Design No. 4,188, dated June 28, 1870.

DESIGN FOR A PAIR OF STATUETTES.

The Schedule referred to in these Letters Patent and making part of the same.

To all whom it may concern:

Be it known that I, NICHOLAS MÜLLER, of the city, county, and State of New York, have invented a new and ornamental Design for a Pair of Statuettes; and I do hereby declare that the following is a full, clear, and exact description thereof, which will enable those skilled in the art to make and use the same, reference being had to the accompanying photograph forming part of this specification, in which the design is represented in perspective.

This invention relates to a design for a pair of statuettes,

Figure 1 representing a school-boy in midwinter on his way to school, and

Figure 2, the mate of fig. 1, represents an errand-girl.

The school-boy has his hands in his coat pockets. The coat is closely buttoned up. Under his left arm he carries a bundle of books. A thick shawl or com-

forter is tied around his neck. His head-covering consists of a cap, which nearly reaches his eyes.

The errand-girl wears a short dress, extending a little below the knees. She is muffled up in a shawl which covers the entire upper portion of her body, exposing only the face, with a curl of hair protruding from each side of it. In her right hand she holds a small pitcher.

The base on which each figure stands (being the same for both) is round, and ornamented, as seen in the photograph.

What I claim as my invention, and desire to secure by Letters Patent, is—

The design for a pair of statuettes, singly and combined, as herein shown and described.

Signed this 26th day of May, 1870.

Witnesses:

NICHOLAS MÜLLER.
